US0D1027450S

(12) **United States Design Patent** (10) Patent No.: **US D1,027,450 S**
(45) Date of Patent: ** May 21, 2024

(54) **STORAGE CADDY**

(71) Applicant: **3M INNOVATIVE PROPERTIES COMPANY**, St. Paul, MN (US)

(72) Inventors: **Andrew T. Helgeson**, Oakdale, MN (US); **Connor M. Pelletier-Sutton**, Minneapolis, MN (US); **Angela L. Pan**, Arden Hills, MN (US); **Alonso M. Hernandez**, Minneapolis, MN (US); **Craig D. Thompson**, Inver Grove Heights, MN (US)

(73) Assignee: **3M Innovative Properties Company**, St. Paul, MN (US)

(**) Term: **15 Years**

(21) Appl. No.: **29/811,301**

(22) Filed: **Oct. 13, 2021**

(51) LOC (14) Cl. **09-04**
